US00D956100S

(12) United States Design Patent (10) Patent No.: US D956,100 S
(45) Date of Patent: * Jun. 28, 2022

(54) DISPLAY SCREEN OR PORTION THEREOF
WITH GRAPHICAL USER INTERFACE

(71) Applicant: Apple Inc., Cupertino, CA (US)

(72) Inventor: Christopher Daryl Soli, Mountain View, CA (US)

(73) Assignee: Apple Inc., Cupertino, CA (US)

() Term: 15 Years

(21) Appl. No.: 29/813,726

(22) Filed: Nov. 1, 2021

Related U.S. Application Data

(63) Continuation of application No. 29/781,703, filed on Apr. 30, 2021, now Pat. No. Des. 934,914, which is a continuation of application No. 29/756,735, filed on Oct. 30, 2020, now Pat. No. Des. 918,263, which is a continuation of application No. 29/734,231, filed on May 11, 2020, now Pat. No. Des. 910,689, which is a continuation of application No. 29/712,377, filed on Nov. 7, 2019, now Pat. No. Des. 884,730, which is a continuation of application No. 29/686,832, filed on Apr. 8, 2019, now abandoned, which is a continuation (Continued)
